UNITED STATES PATENT OFFICE.

ANTON EVENSEN, OF CHICAGO, ILLINOIS, ASSIGNOR OF ONE-HALF TO
CHARLES R. HANNAN, OF COUNCIL BLUFFS, IOWA.

EXPLOSIVE-ENGINE.

SPECIFICATION forming part of Letters Patent No. 721,872, dated March 3, 1903.

Application filed November 2, 1900. Serial No. 35,203. (No model.)

To all whom it may concern:

Be it known that I, ANTON EVENSEN, of Chicago, in the county of Cook and State of Illinois, have invented certain new and useful 5 Improvements in Explosive-Engines; and I do hereby declare that the following is a full, clear, and exact description thereof, reference being had to the accompanying drawings, and to the letters of reference marked thereon, 10 which form a part of this specification.

This invention relates to single-acting gas-engines of that class wherein the charge is admitted to the cylinder at every revolution of the crank-shaft under normal conditions 15 of working from a separate compression-chamber through a valve controlled by an automatic governing device.

The invention consists in the matters hereinafter set forth, and more particularly pointed out in the appended claims.

In general terms the engine illustrated in the accompanying drawings comprises a single-acting engine wherein balance is obtained by having the piston and cylinder reciprocate in 25 opposite directions, both being attached by the usual connecting-rod and wrist-pin connections to oppositely-extending cranks secured to a main shaft. A compression-cylinder and a piston are in operative connection 30 with the main cylinder and a suitable fuel-supply chamber or tank, and the compressed carbureted air or gas is led therefrom to a compression coil or chamber. From hence it is 35 discharged through a valve into the main cylinder, said valve being automatically controlled by a governing device upon the main shaft through connecting tappets, rods, and rock-arms.

In the drawings, Figure 1 is a plan view 40 showing two engines each of which embodies the salient features of my invention, both engines being coupled in the usual quartering relation to a single main shaft and both being controlled by the same governing device. 45 Fig. 2 is a side elevation of one of the engines. Fig. 3 is a view, partially in longitudinal section, showing the piston, cylinder, crank-shaft, and connecting-rods of one of the engines. Fig. 4 is a view in elevation of 50 the cylinder and piston, with their connections, and in longitudinal section of the com-

pression-cylinder and piston, with the valves thereof. Fig. 5 is a sectional view on line 5 5 of Fig. 1. Fig. 6 is a plan view, partially in elevation and partially in section, showing 55 the main shaft, crank-arms, and wrist-pins of the coupled engines.

Referring to the drawings and the general disposition and arrangement of the main parts of the duplicate engines shown, A represents 60 a cylinder closed at its outward end and having sliding connection with parallel guide-rods B. Said rods form a part of an engine-frame, being connected at their ends by suitable cross-pieces B'. Said cylinder A is connected by a connecting-rod a with the main crank-shaft C, which is mounted in bearings 65 c on the guide-rods B. Said cylinder A is fitted with a piston D, which has a connecting-rod d pivotally secured at one end to the 70 piston-stem and at the other to a wrist-pin d', fastened at the end of a crank-arm of equal length to the cylinder crank-arm and secured opposite thereto on the main shaft C.

O represents the casing of a valve which 75 is preferably connected with the cylinder-head a', said valve being of a rotary or rocking type and being operated by any preferred form of mechanism.

Referring specifically to the details of the 80 cylinder and piston connections, the cylinder A is provided at either end with laterally-projecting lugs a². Said lugs have sliding engagement with the guides B. The cylinder is fitted with a piston-head formed of the 85 usual spiders d² and expansion-rings d³, secured between the spiders, said spiders and rings being centrally secured on the piston-stem d⁴. Said piston-stem is provided at its outer end with the usual pin d⁵, to which is 90 secured one end of the piston-connecting rod d, which has the usual bearing-brasses, strap, and key. The other end of said connecting-rod d is pivotally secured by the usual split bearing and brasses on the wrist-pin d'. Said 95 wrist-pin d' is attached to one arm of the double crank G. The other end of said crank carries a similar wrist-pin a³. On the side of the cylinder A an exterior boss a⁴ is cast near the open end of the cylinder, said boss forming a convenient surface on which a pivot-pin a⁵ is secured. The inner end of the cyl-

inder crank-rod a is pivotally secured to the pivot-pin a^5 by the usual bearing-brasses, strap, and key. The outer end of said connecting-rod a is likewise secured to the pin a^3 by the usual split bearing. From this method of connection it follows that an expansion of gas or air in the cylinder between the piston and head forces the piston and cylinder in opposite directions. They bear, 10 through their connnections upon the opposite ends of the crank G , in opposite directions. Said cranks being rigid with the main shaft C , the latter is rotated in its bearing, and as the forces acting upon the opposite arms of 15 the crank G are equal and in point of direction opposite there is a minimum lateral strain upon the main-shaft bearings, said pressure or strain being completely overcome at the dead-center and having but slight effect at the 20 point of maximum leverage. If two cylinders are coupled with their crank-arms in the usual relation of one hundred and eighty degrees to each other, as shown in Fig. 1, the torsional effect upon the shaft is practically the only 25 stress under which it operates.

The valve actuating and governing mechanism may be of any preferred form, but as herein described is of a type illustrated and claimed in an application, Serial No. 50,616, 30 filed by me March 11, 1901, for a valve actuating and governing mechanism for explosive-engines and is not specially claimed herein. Referring to the construction, in general terms, of said valve actuating and governing 35 mechanism, H is the usual fly-wheel, keyed to the outer end of the main shaft C . A cam-disk I , concentric with the main shaft, is mounted loosely thereon next to the inner face of the driving-wheel H and secured to the main 40 fly-wheel by weighted bell-crank levers K , so disposed that varying positions of the levers due to changes in the engine speed vary the angular relations of the disk and fly-wheel. Said disk I carries on its face remote from the 45 fly-wheel H a cam-groove i^2 . Said cam-groove is connected operatively with rocker-arms L and L' , and rods L^2 with tappet-blocks $N N'$, which are secured in proximity to the cylinder-head a' of the cylinder.

50 Referring to the valve proper, it comprises a casing O and plug O' , the valve being of the oscillatory or rocking type. The casing has the form of a cylinder, as herein shown, extending across the outer face of the cylinder-head a' , and the valve-plug O' , which revolves therein, is so fitted as to afford feed and exhaust ports to the cylinder and cut-off at the proper positions of the cylinder and piston. A valve-stem o^4 , which projects 55 through the casing O , carries at its outer end a rocker-arm R , which engages, by means of a roller r , journaled thereon, the tappets $N N'$, so as to be actuated by the combined shifting motion of the eccentric disk I and 60 the reciprocating longitudinal movement of the cylinder.

65 The device for igniting the charge and ex-

ploding the same at the proper point in the cylinder may be of any preferred form.

Referring now to the details of the compressing and charging device and its connection with the cylinder-valve, F represents a cylinder closed at one end and secured to the main frame in parallel relation to the main cylinder. Preferably it is attached, a little below and to one side of said cylinder, to the cross-piece B' . Said closed end is provided with the usual head f , which has a central aperture f' . Said aperture is connected by a pipe V or other means to a vaporizer or chamber supplying hydrocarbon vapor, or to a source of gas-supply in case a fixed gas be used as fuel. A valve-closure f^2 is seated on the inner end of said aperture, so as to open inwardly toward the cylinder to allow free ingress of the fuel and close to prevent egress thereof when compression takes place. A piston having a hollow piston-head f^3 and a hollow stem f^4 slides in said cylinder, the outer end of the stem being rigidly secured to the outer face of the main-cylinder wall at a point approximately opposite the end of the piston-stroke. The inner face of the piston-head is apertured to connect with the interior duct on the stem, as shown. 95 The fixed end of the hollow piston-stem f^4 is connected by suitable means to a compression-chamber in juxtaposition to the main-cylinder wall, so that it is heated thereby, together with its contents. A convenient way 100 of accomplishing this result is to form the compression-chamber of a metallic coil or half-coil of pipe T , which leads up and over the exterior of the main cylinder A , is doubled back and forth part way around the cylinder-wall, and from thence extends over the cylinder-head a' to the ingress-port o^2 in the end of the valve-casing O . An air-port F^2 is provided in the outer wall of the compression-cylinder F near its closed end, said aperture 110 being fitted with an inwardly-opening valve-closure f^5 .

The operation of the compression-cylinder is as follows: On the return stroke of the main cylinder toward the piston-head it carries with it the hollow piston F' , drawing it toward the outer or open end of the compression-cylinder F , thereby creating a vacuum, so that the gas or vapor from the carbureter is drawn in through the orifice f' past the opening closure f^2 , and air enters through the aperture F^2 , said apertures being so proportioned that the proper relative quantities of air and gas or vapor are admitted. On the outstroke of the main cylinder the commingled gas or vapor and air in the compression-cylinder F are compressed and forced through the hollow stem of the piston into the half-coils T on the top of the main cylinder, a suitable check-valve F^3 being located in the piston-head F' to prevent the return of the gas in the compression-coils to the cylinder on the outstroke of the compression-piston.

115 120 125 130 The operation of the engine mechanism as

a whole is as follows: In the position shown in Fig. 16 the piston-head and cylinder-head are separated slightly, both piston and cylinder being on the "outstroke" and the crank 5 being just past the "dead-center," as hereinbefore described. The valve-ports are in the position shown, both ports being closed and the tappets N and N' being free from the valve rocker-arm R, and the spring-plate r^2 10 holding the valve-closure in the position above indicated. The terminals Q and Q' are at this time just at the point of "breaking." At the explosion of the charge by the spark resulting from the "break" the expansion of 15 the ignited gases forces the cylinder-head and piston-head apart, thereby imparting a rotary motion to the main shaft C and the fly-wheel H through the double-armed crank. Said fly-wheel carries with it in its rotation 20 the usual governing device, which controls the valve in the usual manner. As the piston and cylinder heads separate still farther the uncovering of the auxiliary port a^8 in the side of the cylinder affords a way of escape 25 for the waste gases and products of combustion in the cylinder. As the cylinder-head and piston approach each other on the return stroke the waste gases are forced out through the exhaust-port. Air also freely circulates 30 through the cylinder during a greater part of the cycle and follows the piston-head, thereby cooling the same and keeping the whole at a working temperature. Coincident with this series of movements the compression-piston 35 forces more gas into the compression-coil and draws a fresh charge into the compression-cylinder, as hereinbefore described.

The form of construction of the frame may vary. A convenient method of construction, 40 where extreme lightness is required, is that shown, which comprises the guide-rods B, preferably cylindrical in form and secured at their ends to the cross-ties B', which may be of any market shape. The interreciprocation 45 of the cylinder and piston reduces, by half, the length of the crank-throw, so that the engine is greatly shortened. This obviates the necessity of having great lateral rigidity. This interreciprocation of the piston and cylinder, by which the reaction of the cylinder is conveyed directly as a torsional strain to the shaft instead of being communicated, as in usual types, to the engine-bed, further allows light bearings and light connections 55 with the frame. The main-shaft bearing-bolts do not have to take any shear due to the cylinder reaction, but merely serve as anchor-bolts which hold the "floating" mechanism in place and take up any external strain, such 60 as the pull of a belt or the thrust of a driving pinion. The internal stress and strain of the engine proper are not communicated in any way to the frame, and therefore the latter can be made of skeleton form, as shown. As 65 the balance is nearly perfect, a lighter fly-wheel than usual may be employed. This, together with the lightened frame, is a desidera-

tum when applying the engine to motor-vehicle or launch work.

The parts herein shown and described may 70 be of any convenient design to fit different engine service, and I do not limit myself to the forms and arrangement of parts except as set forth in the claims.

I claim as my invention—

75

1. An explosive-engine comprising a main cylinder having endwise reciprocatory movement, a piston in the main cylinder, a main frame having parallel guides for the main cylinder, guide-lugs on the main cylinder having sliding engagement with said parallel guides, a crank-shaft having oppositely-extending cranks, bearings for said shaft rigidly attached to the engine-frame, and connecting-rods connecting the main cylinder 85 and the piston with the cranks of the crank-shaft.

2. An explosive-engine comprising a main cylinder having reciprocating longitudinal movement, a stationary, separate charge-compressing cylinder arranged parallel with the main cylinder, and a piston for said compression-cylinder the stem of which is rigidly attached to said main cylinder.

90

3. An explosive-engine comprising a main cylinder having reciprocating longitudinal movement, a charge-compressing cylinder and a piston for said compressing-cylinder comprising a hollow head and a hollow stem opening into said head, gas or fuel and air intake valves in said compressing-cylinder and an outlet-valve in said piston-head, said piston-stem being secured at its outer end to said main cylinder.

95

4. An explosive-engine comprising a main cylinder having a reciprocating longitudinal movement, a charge-compressing chamber discharging into said main cylinder, a compression-cylinder arranged parallel with the main cylinder, said compression-cylinder being arranged to discharge into the said chamber, and a piston in the compression-cylinder, the stem of which is rigidly attached to the main cylinder.

100

5. An explosive-engine comprising parallel guide-rods, a main cylinder having sliding connection with said guide-rods and having longitudinal reciprocatory motion thereon, a piston in the cylinder, and a crank-shaft the bearings of which are rigidly connected with 110 said guide-rods and having a double crank connected with the cylinder and piston.

115

6. An explosive-engine comprising parallel guide-rods, a main cylinder having sliding connection with said guide-rods and having longitudinal reciprocatory motion thereon, a piston in the cylinder, a crank-shaft the bearings of which are rigidly connected with said guide-rods and which has a double crank connected with the cylinder and piston, a separate charge-compressing cylinder arranged parallel with the main cylinder, and a piston in said compressing-cylinder the stem of which is rigidly attached to said main cylinder.

120

130

7. An explosive-engine comprising a main cylinder having reciprocating, longitudinal movement, a charge-compressing chamber discharging into said main cylinder, a compression-cylinder, a piston for said cylinder secured by its stem to said main cylinder, a duct leading through said piston and stem to said compression-chamber, a gas or vapor port opening into said cylinder, an air-port in said cylinder, and valves in said duct and ports whereby the outstroke of said piston fills said cylinder with air and fuel or gas, and the in-stroke of said piston compresses the contents of said cylinder and forces it into said compression-chamber.

8. An explosive-engine comprising a main cylinder having reciprocating, longitudinal movement, a charge-compressing cylinder, a piston for said compression-cylinder having its stem rigidly secured to said main cylinder,

and a duct through said piston and stem delivering the charge to said main cylinder.

9. An explosive-engine comprising a main cylinder having reciprocating, longitudinal movement, a charge-compressing chamber discharging into said main cylinder, a compression-cylinder, a piston for said cylinder having its stem secured to said main cylinder, and a duct through said piston and stem opening into said compression-chamber for delivering the compressed charges therein.

In testimony that I claim the foregoing as my invention I affix my signature, in presence of two witnesses, this 30th day of October, A. D. 1900.

ANTON EVENSEN.
